UNITED STATES PATENT OFFICE

HARRY L. ROGERS, OF PHILADELPHIA, PENNSYLVANIA.

SEAT-INDICATOR FOR THEATERS.

1,267,273.

Specification of Letters Patent. Patented May 21, 1918.

Application filed September 17, 1915. Serial No. 51,232.

To all whom it may concern:

Be it known that I, HARRY L. ROGERS, a citizen of the United States, residing at Philadelphia, in the county of Philadelphia and State of Pennsylvania, have invented 5 certain new and useful Improvements in Seat-Indicators for Theaters, of which the following is a specification.

My invention relates to indicators and has 10 for its primary objects a provision of a simple and cheap indicator for use in connection with theater or auditorium seats, whereby to apprise parties entering a theater as to the number and location of vacant 15 seats.

My invention attains the mentioned object by the provision of an indicator associated with each row of seats in a theater, the indicator being placed on the end of a 20 row at a point so as to be seen from the rear of the building.

Other objects will appear when a more thorough understanding of the invention is had from a perusal of the specification and 25 an inspection of the accompanying drawings in which Figure 1 is a side elevation of a theater seat having applied thereto the preferred embodiment of my invention.

Fig. 2 is a rear elevation of the same.

Fig. 3 is a front elevation of the same.

Fig. 4 is an enlarged vertical sectional view of the indicator showing the same in position on the back of a seat.

Fig. 5 is a diagrammatic view of the preferred arrangement of the electrical circuits embodied in the preferred form of my invention and,

Fig. 6 is a detail enlarged view of one form of circuit closer.

Similar reference characters designate 40 similar parts throughout the various views of the drawings, wherein the preferred embodiment of the invention is illustrated, a theater seat shown being of the usual construction having the base frame 1, back 2 and hinged seat portion 3. Usual arm rests 45 are designated 4. The seat 3 is preferably maintained in the position shown in Fig. 1, when unoccupied, by means of a suitable 50 spring 5.

My invention as applied embodies a housing 6 having a hinged front wall 7 provided with a plurality of apertures 8 over which a colored transparent plate 9 is placed, said plate being maintained on the front wall 7 by a flange 10. The housing 6

is maintained on the seat back 2 by means of angular pieces 11. It is to be understood that the housing may be detachably connected with the back so as to facilitate removal for repair or replacements. A plurality of indicating lamps 12 are provided, said lamps being mounted upon the rear wall of the housing 6 and adapted to project their rays through the openings 8 in the front 65 wall 7. Suitable shields 13 are carried by the front wall 7 and are adapted to cover each of the lamps so as to protect the same and direct the rays thereof through said openings. The lamps are connected in a 70 manner hereinafter set forth by means of conductors 14.

In Fig. 5 I have illustrated in diagrammatic form the preferred arrangement of electrical circuits embodied in the present 75 invention. Seats are designated S 1, S 2, S 3, and S 4. The main source of electrical energy is supplied by conductors 15 from which branch conductors 16 and 17 extend, the conductor 17 being what is commonly 80 termed a common return wire. A plurality of branch conductors tapped at various points through the length of the conductors 16 extend to each of the seats shown, said conductor being designated 18 and having 85 interposed therein, suitable circuit closing means associated with the seats and described in detail hereinafter. The conductors 18 extend to the lamps 12 shown in diagrammatic form. Normally the circuits to 90 the lamps 12 are closed, that is, when the seats are unoccupied. However, as soon as a seat is occupied, the lamp designating said seat is extinguished and seats remaining unoccupied continue to indicate such a condition by the lamps representing the same 95 remaining lighted.

In Fig. 6 a form of circuit closer is shown. The back 2 and hinged seat 3 are provided with insulating blocks 19 and 20 placed on 100 their marginal edges at adjacent points. The blocks 19 and 20 carry binding posts 22 to which the conductors 23 may be attached. A pair of L-shaped contacting plates 24 and 25 are provided on the blocks 105 19 and 20 and are adapted when the seat 3 is in the position shown in Fig. 1 to engage and close the circuit to corresponding lamp for said seat.

When applied in proper position, the 110 housings are carried upon the outer side of the end seat of each row, a corresponding

number of lamps being placed in the housings to the number of seats in the row. The openings 8 are placed so that the rays from the lamps 12 may be readily seen from the rear of the theater and parties entering may readily observe from the back of the theater the number and location of the seats unoccupied, thereby avoiding much confusion and inconvenience in locating a seat in a dark auditorium such as would be the case in a moving picture house.

The main feed conductors 15 may be made into various sub-feeding sections for various sections of seats in a theater. It will be noted that when the front wall of the housing is moved to the open position shields 13 will be removed from the lamps allowing the latter to be replaced when necessary.

From the above description taken in connection with the accompanying drawing it is thought that a clear and comprehensive understanding of the construction, operation and advantages of my invention may be readily gathered, and while I have shown and described the same as embodying a specific structure, it will be understood that I reserve the right to make changes in said structure which do not depart from the spirit and scope of the invention is claimed.

What I claim is:

1. In a device of the class described, the combination of a chair comprising a back and pivotally mounted seat, L-shaped plates fixedly mounted upon the marginal edge of said back and said seat whereby said contact plates will overhang the inner surface of said back and the upper surface of said seat, thereby causing said contact plates to be in alinement with each other, whereby as said

seat is swung to an elevated position said plates will be clamped between said seat and said back for forming a positive circuit closure.

2. In a device of the class described, the combination of a seat comprising a back and pivotally supported seat portion spring members for urging said seat portion in one direction, L-shaped contact plates mounted upon the marginal edge of said back and said seat portion, whereby portions of said contact plates will overhang the inner surface of said back and the upper surface of said seat portion whereby when said seat portion is in an elevated position, said contact plates will be clamped between said back and said seat portion for positively closing a circuit.

3. In a device of the class described, the combination of a chair comprising a back having a pivotally supported seat, means for urging said seat toward an elevated position, insulating blocks carried upon the marginal edges of said back and seat, L-shaped contact plates mounted upon said insulating blocks and overhanging the inner surface of said back and the upper surface of said seat, binding posts projecting from said plates whereby conductors may be applied thereto, and said contact plates being clamped between said back and seat when said seat is in an elevated position, thereby positively closing the circuit.

In testimony whereof I affix my signature in presence of two witnesses.

HARRY L. ROGERS.
